UNITED STATES PATENT OFFICE.

CHARLES H. TOWERS, OF PHILADELPHIA, PENNSYLVANIA.

ROCKING-CHAIR-OPERATED DEVICE.

1,187,943.

Specification of Letters Patent. Patented June 20, 1916.

Application filed September 1, 1914. Serial No. 859,637.

To all whom it may concern:

Be it known that I, CHARLES H. TOWERS, a citizen of the United States, residing in the city and county of Philadelphia, State 5 of Pennsylvania, have invented a new and useful Rocking-Chair-Operated Device, of which the following is a specification.

My invention consists of a device such as a fan which is adapted to be operated by 10 mechanism connected with a rocking chair as the prime motor therefor, said mechanism involving a clutch member which may be placed into and out of contact with a gear wheel, a clutch member which may be 15 placed into contact with said wheel as a stop or brake therefor, and a flexible shaft connected with said gear wheel, the same being adapted to be deflected according to different positions of the chair or the fan support, and serve to impart motion through intermediate parts to the fan.

It consists also of details as will be hereinafter described and pointed out in the claims.

25 The invention is satisfactorily illustrated in the accompanying drawing, but the important instrumentalities thereof may be varied, and so it is to be understood that the invention is not limited to the specific design 30 tails shown and described.

Figure 1 represents a partial side elevation and partial vertical section of a rocking-chair operated fan embodying my invention. Fig. 2 represents a bottom plan view of the fan stand thereof on an enlarged scale. Fig. 3 represents a horizontal section of a portion on an enlarged scale on line $x-x$ Fig. 1. Fig. 4 is a section on the line $y-y$ of Fig. 1 on an enlarged scale. 40 Fig. 5 is a view at right angles to Fig. 4. Fig. 6 represents a partial side elevation and partial vertical section of the clutch mechanisms and connected members on an enlarged scale. Fig. 7 represents a partial 45 plan view and partial horizontal section thereof on a line $z-z$ Fig. 6. Fig. 8 represents a transverse vertical section on line $a-a$ Fig. 6. Fig. 9 represents a partial elevation and a partial section of a detached portion.

Similar numerals of reference indicate corresponding parts in the figures.

Referring to the drawings:—1 designates a casing which is connected with the rocker 50 2 for a rocking chair toward either end thereof, as shown at the bottom of Fig. 1.

In order to clamp said casing to said rocker, the side wall of the former has connected with it the lower end of the swinging plate 3. To the upper end thereof is connected 60 by a conical head and socket the inner end of the stem 4 whose outer end is swiveled on the cross-bar 5 of the angular frame 6 which latter is supported on a bracket 7 by means of the screws 8. The outer portion of said stem is screw-threaded for engagement of the nut 9 which is adapted to bear against said bar 5. Interposed between the latter and the plate 3 is the spring 10, the object of which is to press the plate 3 toward the 70 side of the casing 1, while the stem 4 is adapted to draw said plate from said casing by which provision the plate 3 may have its angle adjusted to the side of the rocker as evident on reference to Fig. 8.

Secured to the outer vertical limb 11 of the frame 6 by the screws 12 is the block 13 in which is fitted the screw stem 14 whose head 14^x is adapted to engage the side of the rocker opposite to the plate 3, it being noticed that owing to the screw 12 the angle of the block may be changed and so adjust its head 14^x to the angle of said side of the rocker, it being noticed also that when the plate 3 and the head 14^x of the screw are 80 applied to the rocker and said screw properly rotated, the casing 1 may be firmly clamped to the rocker and so move therewith in the motions of the chair.

Within the casing at the center thereof 90 and secured thereto by the screw 15 is the post 15^x on which is mounted the lever 16, the lower end whereof is supported on the roller 16^x, it being noticed that said lever is freely movable in a recess 17 in the 95 peripheral wall of said casing.

Within the casing is the gear wheel 18 which is mounted on the post 15^x and has on its side the circular shoulder or annulus 19 formed with or secured firmly thereto in 100 any suitable manner.

On the side of the lever 16 is the bar 20, the lower end of which has a bifurcation 21 which straddles the screw 22 thus forming a 105 pivotal connection for said end of said bar with said lever. On the side of the upper end of said bar are the studs 23 which are disposed on the opposite periphery of the annulus 19 and are oblique to each other so as to form in connection with said bar a 110 clutch which when the lever 16 rises is adapted to tighten against said annulus so

as to impart rotary motion to the latter, and consequently to the gear wheel 18.

Connected with the lever 16 and bearing against the bar 20 is the spring 24 which 5 when the lever 16 descends is adapted to remove said studs 23 from their clutching action on the annulus 19 without operating the gear wheel 18 or interfering with the descent of said lever.

10 Mounted on the side walls of the casing 1 is the pinion 25 which meshes with the gear wheel 18 and is adapted to receive motion therefrom and impart it to the flexible shaft 26, one end of which is connected with the shaft 27 of the pinion 25.

Within the casing 1 is the plate 28, the lower end of which is bifurcated as at 29 so as to be fitted over the shaft 27 as a free bearing therefor. The upper end of said 20 plate 28 has on its side the studs 30 which are arranged obliquely to each other and adapted to engage the opposite peripheries of the annulus 19 as a friction clutch or brake therefor, said studs on the ascent of 25 the lever 16 allowing said annulus to ride freely between the same, but on the descent of said lever, said upper end of the plate is raised by the action of the spring 31 which is connected with said plate and the adjacent 30 part or shoulder 32 of the wall of the casing 1. When the studs 30 are pressed into contact with the annulus and caused to bite or clutch the same and so prevent the motion of the annulus and consequently of the gear 35 wheel 18, the pinion 25 and the shaft 27 of the latter, the flexible shaft 26 owing to its coiled nature, is prevented from unwinding and reversing.

33 designates the fan stand of the device 40 the base 34 therof being mounted on the feet 35 so that said base is somewhat elevated above the floor on which the stand is placed. Mounted on the underside of said base 34 is a system of gearing 36, one member 45 37 of which a bevel pinion is connected with the end of the flexible shaft 26 opposite to the casing 1, said end being passed under the base 34 so as to reach said member 37. Another member of said gearing 38, a spur 50 wheel is fitted on and secured to the lower end of the shaft 39, which is passed vertically through said column and adapted to rotate therein. Connected with the upper end of said shaft 39 in the head or cap 40 of the stand 39 is the bevel pinion 41, which meshes with the bevel pinion 42, the latter being connected with a horizontally arranged auxiliary driving shaft 43 whose bearings are on the cap 40.

60 Connected with the side of the cap is the sleeve or tubular member 44, within which is mounted the supplemental driving shaft 45 to whose outer end is screwed, bolted or otherwise secured the rotary fan 46 which is 65 formed of suitable blades, and a hub carry-

ing the same, said hub being fitted on the shaft 44 and secured thereto by the screw 47 or other suitable means. The side of the cap 40 is formed with the fork 48 to which is attached by means of the screws or bolts 49 a similar fork 44* on the adjacent end of the sleeve 44, whereby said sleeve and consequently the fan is supported on the stand adapting said sleeve to be placed at different angles, the position of which may be imparted to the fan 46, whereby the latter may be raised or lowered in oblique directions and set horizontally on the stand as desired, it being noticed, however, that the shaft 45 is coupled with the shaft 43 so as to receive its power from the latter. This coupling is accomplished by means of the collar 48* and the finger 50 the former being firmly fixed to the outer end of the shaft 43, the latter being formed with the eye 51, which is freely mounted on the axle 52, which occupies with said eye the recess 53 in the inner end of the shaft 45, within the collar 48* said axle being secured to the walls of said recess. The outer terminal of the finger 50 freely occupies the opening 54 in the side wall of the collar 48* so that when the shaft 43 rotates it imparts motion to the collar 48*, the finger 50, the shaft 52 and consequently to the fan shaft 45 whereby the fan is rotated. When the screws 49 are loosened, the angle of the sleeve 44 may be varied, but the finger 50 remains in the opening 54, regardless of the angular position of the shaft 45, and thus the two shafts 45 and 43 are coupled, and the motion of the shaft 43 is communicated to the shaft 45 under all circumstances.

Certain of the shafts of the device are provided with ball bearings whereby they are adapted to run with all of the advantages 105 of the same.

The operation is as follows:—When the chair is occupied and rocked and the ends of the rockers thereof descend, as the casing 1 is set back from either of said ends, the same rises and carries with it the lever 16 which is fulcrumed on the floor by the roller 16*. The clutch bar 20 is raised with said lever and slightly turned by the same whereby the studs 23 bite or clutch tightly 115 the annulus 19 and cause a rotation thereof, this then being imparted to the spur wheel 18 and the pinion 25 and consequently to the flexible shaft 26 and by the intermediate gearing and members of the fan. The rotation of the annulus 19 being positively occasioned by the clutch studs 23, said annulus slides freely between the clutch studs 30 120 overcoming the pressure of the spring 31 against the plate 28 that carries said studs 30. As soon as the lever 16 has rendered its up-stroke and begins to descend with the ascent of the rocker, the spring 24 operates the bar 20 axially to a slight extent 125 in a direction to move the studs 23 from 130

their holding action on the annulus when said studs slip on the latter and the plate 28 is immediately moved axially by the action of its connected spring 31 whereby 5 the clutch studs 30 are tightened against and bite the annulus and act as a brake to prevent rotation of the annulus, the gear wheel 18 and the pinion 25 preventing any possible uncoiling or reverse motion of the 10 flexible shaft, although the latter has its convolutions sufficiently coiled to continue the rotation of said shaft, while the end of the lever 16 descends with the casing, but the rocker again causes the ascent of the 15 casing and the lever 16 when the other members repeat the operations as have been explained.

It is evident that the flexible shaft permits the chair and the stand to be moved 20 and placed where desired on a floor within the length of said shaft without effecting the operation of the latter and consequently of the fan.

Having thus described my invention what 25 I claim as new and desire to secure by Letters Patent, is:—

1. A rocking device, a lever, a casing, a 30 gearing wheel in the latter, a shaft in said casing for said wheel, one end of said lever being mounted on said shaft, the other end thereof being adapted to be fulcrumed on a floor, said casing being connectible with 35 said rocking device, a supplemental shaft on said casing, a pinion on the latter adapted to be operated by said gear wheel, a flexible shaft connected at one end with said supplemental shaft, a member to be rotated, a shaft carrying said member, a stand member, a driving shaft on said 40 stand, operative gear between the driving shaft and said member carrying shaft, and operating gear between said driving shaft and said flexible shaft, the end of the latter opposite to said casing being connected with 45 a shaft of the last named operating gear.

2. In a rocking-chair-operated device such as a fan, a casing connectible with the 50 rocker of a chair, a lever mounted on said casing at the center thereof and adapted to be fulcrumed on a floor, a flexible shaft, means actuated by movement of said lever imparting motion to said shaft, and fan-operating mechanism operatively connected with said flexible shaft.

55 3. In a rocking-chair-operated device, such as a fan, a casing connectible with the rocker of a chair, a gear wheel in said casing, a lever mounted on said casing adapted to be fulcrumed on a floor, a flexible shaft 60 operatively-connected with said gear wheel, mechanism engaging said lever and gear wheel adapted to operate the latter, and fan-actuating mechanism operatively connected with said flexible shaft.

65 4. In a rocking-chair-operated device,

such as a fan, a casing connectible with the rocker of a chair, a gear wheel in said casing, a lever mounted at one end on said casing and adapted to be fulcrumed at its free end upon a floor, a flexible shaft, and connections whereby said shaft is actuated by movement of said lever, and a fan shaft and gearing intermediate of the latter, and said flexible shaft adapted to operate the fan.

5. In a rocking-chair-operated device, 75 such as a fan, a fan shaft, a gear wheel, a pinion adapted to mesh with said gear wheel, a power-conveying shaft connected with the shaft of said pinion and operatively connected with the fan shaft, brake 80 mechanism and connections to prevent reverse motion of said power-conveying shaft, a casing connectible with a rocker of a chair and a lever pivotally supported at one end on said casing and adapted to be fulcrumed at its other end on a floor.

6. In a rocking-chair-operated device, such as a fan, a fan shaft, a gear wheel, a pinion adapted to mesh with said gear wheel, a power-conveying shaft connected 90 with the shaft of said pinion and operatively connected with the fan shaft, a casing connectible with a rocker of a chair, a lever fulcrumed at one end on the floor and at the other end pivotally mounted on the 95 casing, and means actuated by said lever for actuating said power-conveying shaft.

7. In a rocker-operated device, such as a fan, a shaft carrying said device, a lever adapted to the raised and lowered, a casing 100 on which said lever is mounted, a gear wheel in said casing, an annulus on the side of said wheel, operative connections between said wheel and shaft, a clutch bar movably mounted on the said lever, and studs on said 105 bar adapted to occupy positions on the opposite peripheries of the said annulus and to tightly engage therewith, said studs being arranged obliquely to each other.

8. In a rocker-operated device, such as a 110 fan, a shaft carrying said device, a lever adapted to be raised and lowered, a casing on which said lever is mounted, a gear wheel in said casing, an annulus on the side of said wheel, operative connections between said 115 wheel and shaft, a clutch bar movably mounted on the said lever, studs on said bar adapted to occupy positions on the opposite peripheries of said annulus and to tightly engage therewith, said studs being arranged 120 obliquely to each other, and a resilient device connected with said bar and lever for throwing off said studs from said annulus.

9. In a rocker-operated device, such as a 125 fan, a shaft carrying said device, a casing, a gear wheel on said casing, an annulus on said wheel, means for rotating said annulus, a pinion meshing with said gear wheel, operative connections between said wheel and shaft and a movable plate in said casing, 130

and studs on said bar adapted to occupy positions on the opposite peripheries of said plate and be held free therefrom in one position of said plate, said studs being arranged 5 obliquely to each other.

10. In a rocker-operated device, such as a fan, a shaft carrying said device, a casing, a gear wheel on said casing, an annulus on said wheel, means for rotating said annulus, 10 a pinion meshing with said gear wheel, operative connections between said wheel and shaft and a movable plate in said casing, studs on said bar adapted to occupy positions on the opposite peripheries of said 15 plate and to be held free therefrom in one position of said plate, said studs being arranged obliquely to each other, a resilient device connected with said plate and casing for forcing said studs into tight engagement 20 with said annulus and mechanism intermediate of said gear wheel and said device carrying shaft.

11. In a rocker-operated device, such as a fan, a stand, a driving shaft therein, an 25 auxiliary driving shaft, gearing connected with said shafts, a supplemental driving shaft, a coupling for said supplemental and auxiliary shafts embodying a finger and con-

nections adapted to insure rotation of said shaft, and the device, such as a fan connected with said supplemental shaft, said coupling adjustably connecting the bearings of the supplemental and auxiliary shafts and being adapted to place said supplemental shaft and the fan thereon at different angles. 30 35

12. In a rocker-operated device, a stand, a plurality of shafts on said stand, means for operating one of said shafts, a coupling for said shafts, a device such as a fan connected with the other shaft, said coupling 40 being composed of a collar on one of said shafts, the peripheral wall of said collar having an opening therein, the adjacent end of the other shaft being adapted to enter said collar, a finger movably mounted on said 45 end of the other shaft and being adapted to freely occupy said opening in said collar, and means for adjustably connecting the bearing of said supplemental and auxiliary shafts adapting the bearing of the supplemental shaft and consequently the fan to be 50 set at different angles.

CHARLES H. TOWERS.
